(57) **CLAIM**

The ornamental design for a bathtub mat, as shown and described.

DESCRIPTION

FIG. 1 is a perspective view of a bathtub mat in a folded position.

FIG. 2 is an alternate perspective view of the bathtub mat in extended flat.

FIG. 3 is a front elevational view thereof, the rear elevational view being a mirror image of the front view.

FIG. 4 is a top plan view thereof.

FIG. 5 is a bottom plan view thereof.

FIG. 6 is a left side elevational view of the bathtub mat; and, FIG. 7 is a right side elevational view thereof.
